(57) **CLAIM**

The ornamental design for a pour spout mason jar lid with screw closure, as shown and described.

DESCRIPTION

FIG. 1 is a top front perspective view of a pour spout mason jar lid with screw closure, showing my new design;

FIG. 2 is a bottom front perspective view thereof;

FIG. 3 is a front elevation view thereof, the rear elevation view being a mirror image thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a top front perspective view thereof, shown in a closed condition.

The broken lines shown in the drawings depict portions of the article that form no part of the claimed invention. The dot-dash lines represent the boundaries of the claim and form no part thereof.

1 Claim, 4 Drawing Sheets
